[57] CLAIM

The ornamental design for a channel cap extrusion for
glass block and the like, as shown and described.

DESCRIPTION

FIG. 1 is a fragmentary perspective view of a channel
cap extrusion for glass block and the like showing my
new design;

FIG. 2 is an end elevational view thereof;

FIG. 3 is a fragmentary bottom plan view thereof;

FIG. 4 is a fragmentary side elevational view thereof;
FIG. 5 is a fragmentary perspective view of a second
embodiment of a channel cap extrusion for glass block
and the like showing my new design;

FIG. 6 is an end elevational view thereof;

FIG. 7 is a fragmentary bottom plan view thereof; and,

FIG. 8 is a fragmentary side elevational view thereof.
The broken line showing of portions of glass block is for
illustrative purposes only and forms no part of the
claimed design.
